HAIR-WAVING ROD

Rose E. Melaro, Oakmont, Pa.

Application July 10, 1948, Serial No. 147,491

Term of patent 14 years

(Cl. D86—10)

To all whom it may concern:

Be it known that I, Rose E. Melaro, a citizen of the United States of America, residing at Oakmont, in the county of Allegheny and State of Pennsylvania, have invented a new, original, and ornamental Design for Hair Waving Rod, of which the following is a specification, reference being had to the accompanying drawing, forming part thereof.

Fig. 1 is a view in front elevation of a hair waving rod showing my new design;

Fig. 2 is a view in front elevation of the hair waving rod turned 90° from that shown in Fig. 1; and

Fig. 3 is a view in end elevation of the hair waving rod shown in Figs. 1 and 2.

Fig. 4 is an isometric view of the hair waving rod as shown in Figs. 1 and 2.

My new design of hair waving rod is characterized by a single piece rod having adjacent spool and cylindrical sections, and the ends of the rods being of the same diameter as the cylindrical section. The surface of the rod is provided with a plurality of grooves that extend

for substantially the full length of the cylindrical section and a portion on the other end of the spool section, leaving a cylindrical portion at each end of the rod and being further characterized by a slot in each end face of the rod.

I claim:

The ornamental design for a hair waving rod, as shown and described.

ROSE E. MELARO.
